ELWOOD C. HALL, OF NEW YORK, N. Y., ASSIGNOR OF ONE-HALF TO
ALBERT C. WOODWORTH, OF NEW YORK, N. Y.

CAR-FENDER.

No. 796,509.

Specification of Letters Patent.

Patented Aug. 8, 1905.

Application filed December 5, 1904. Serial No. 235,478.

To all whom it may concern:

Be it known that I, ELWOOD C. HALL, a citizen of the United States, and a resident of the city of New York, borough of Manhattan, in the county and State of New York, have invented a new and Improved Car-Fender, of which the following is a full, clear, and exact description.

This invention relates to car-fenders, and especially to the class carried by trolley-cars or street-cars.

The object of the invention is to provide a fender of simple construction which will be normally disposed in an inoperative position well beneath the body of the car, but which can be instantly sprung into operative position, so as to catch an object lying upon the track before the car.

Reference is to be had to the accompanying drawings, forming a part of this specification, in which similar characters of reference indicate corresponding parts in all the views.

Figure 1 is a perspective view of the forward portion of a car and illustrating the fender applied in practice and carried under the forward portion of the car-body. Fig. 2 is a vertical section taken through the forward portion of the car-body and through the fender, showing the fender in its normal or inoperative position. Fig. 3 is a view similar to Fig. 2, but representing the fender in its advanced or operative position. Fig. 4 is a vertical section through a portion of the fender and illustrating especially the manner of supporting and releasing the same for action; and Fig. 5 is a rear face view of a bracket, two of which constitute the main supports for the fender, certain parts appearing in section.

Referring more particularly to the parts, 1 represents a car to which my fender 2 has been applied, the same being normally disposed under the forward portion of the car-body, as illustrated.

The construction of the fender and means for supporting the same will now be described. At suitable points under the car-floor 3 I attach brackets 4, which brackets present cheeks or side plates 5, to which oppositely-disposed fender-arms 6 are pivotally attached in any suitable manner, as at 7. The bodies of these arms 6 are disposed below the pivot-point 7, but their upper extremities project therebeyond and preferably rearwardly, as shown, so that each may form a pivotal connection at 8

with a knuckle 9, carried at the extremity of a stem or plunger 10. These plungers pass through openings 11 in the rear faces of the brackets 4 and are provided at their extremities with enlarged heads 12, securely attached to the same. Against these heads springs 13 thrust, the forward extremities of said springs thrusting against the rear faces 14 of the brackets, as shown.

The lower extremities of the fender-arms 6 are preferably offset forwardly, as indicated at 15, and these arms make pivotal connection at 16 with a transversely-disposed fender-beam 17. To this beam 17 a plurality of curved fingers 18 attach, the same being disposed substantially parallel and projecting forwardly, so as to form a cradle or swinging platform 19, adapted to support a body falling thereupon. The forward extremities of these fingers 18 are separated by thimbles or sleeves 20, through which a transverse trip-rod 21 passes, so that the entire cradle constitutes a firm and substantial construction.

A suitable pair of the fingers 18, preferably the two outside fingers, have shackles 22 attached thereto, which shackles include pivotal connections 23, as shown, uniting the members 24 and 25, which constitute the shackles. The members 24 are rigidly secured to the fingers, and the members 25 attach to cushion-bars 26. These cushion-bars are connected near their extremities by transverse bars 27, with which they unite to form a cushion-frame, and these bars 27 are connected by a plurality of resilient cushion-strips 28, disposed transversely between them, as shown. These strips 28, in connection with the frame to which they attach, constitute a cushion 29, which constitutes a guard for the bumper 30 of the car when the fender is in its operative position, as shown in Fig. 3. Preferably near their middle portions the cushion-bars 26 are provided with a plurality of openings 31, which facilitate the adjustable attachment of links 32, the remote extremities of said links being pivotally attached to bracket-plates 33, attached at the under side of the car-body, as indicated.

The springs 13 referred to above evidently normally operate to maintain the plungers 10 in substantially the position in which they are shown in Fig. 3, and hence they operate normally to maintain the fender-arms 6 in a forward relation, also shown in the same figure.

When the parts of the fender are disposed in this relation, evidently the cradle 19 constitutes effective means for catching a body lying on the track in front of the advancing car. Corresponding with this advanced and depressed position of the cradle the cushion 29 will dispose itself, as indicated in Fig. 3, in an upwardly-inclined relation, lying directly in front under the bumper 30, constituting a substantial guard to prevent the body in the fender from striking the bumper.

Arrangement is made for normally maintaining the fender in a folded or inactive position under the car-body. Referring especially to Figs. 2 and 4, beneath the car-floor 3 at a suitable point a throat 34, preferably inclined, as shown, is formed between a pair of oppositely-disposed throat-brackets 35 and 36, the former of which is disposed forwardly and provided with a short upwardly-turned lip 37 for a purpose which will appear more fully hereinafter. The throat-bracket 36 is preferably elongated with respect to its mate and is formed with an elongated rearwardly-projecting lip 38, the purpose of which will also appear hereinafter. Preferably upon the rear bracket 36 a catch or dog 39 is pivotally attached at 40, so that the body of the same inclines downwardly in the same general direction as the brackets. The forward or lower extremity of the catch 39 is formed with a head 41, presenting an abrupt shoulder 42 and preferably a curved outer edge 43, and this head normally disposes itself within the throat 34, as indicated. It is resiliently held in this position by means of a suitable helical spring 44, which surrounds a link 45, pivotally attached at 46 to the upper extremity of the dog 39. The forward extremity of this spring 44 thrusts against a guide-bracket 47, attached to the under side of the floor, through which guide-bracket the link 45 passes, as shown. The rear extremity of the spring thrusts against a collar 48, which is rigidly attached to the link. Evidently from this arrangement the spring normally operates to maintain the catch or dog 39 in the position shown. The forward extremity of the link 45 attaches, pivotally, at 49 to the core 50 of a solenoid 51, and the coils of this solenoid are in connection with a grounded circuit 52, which circuit is adapted to be closed automatically by the controller 53 of the car. Any suitable arrangement may be adopted for this purpose, such as that indicated, in which a collar 54 on an arbor 55 engages a contact-plate 56 when the lever 57 is beyond its "off" position. As illustrated, the circuit 52 leads from the contact-plate 56 through the solenoid-coil and to the ground at 58.

At the point upon the beam 17 which lies opposite the throat 34 a tongue 59 is pivotally attached in any suitable manner, this tongue projecting upwardly and rearwardly from the beam, as indicated. Near its upper

extremity it is provided with an opening 60. When the fender is thrown into its inactive position, the arms 6 rotate rearwardly upon the pivots 7, and the rear extremity of the tongue 59 may be made to enter the throat 34 and when pressed into the same sufficiently the head 41 of the dog 39 will co-operate with the tongue, so as to lock the same in the throat, as indicated in Fig. 4, the upper edge of the opening 60 bearing against the shoulder 42 of the dog 39. The purpose of the outwardly-curved lips 37 and 38 will now appear, as these lips will evidently facilitate the passing of the tongue into the throat, and the purpose of the curved edge 43 on the head 41 will also be now evident, as the presence of this edge facilitates the lateral displacement of the dog by the advancing tongue.

An adjustable connection is made between the tongue 59 and the beam 17 for the purpose of enabling the height of the forward portion of the cradle to be nicely adjusted. For this purpose the lower extremity of the tongue 59 is provided with a rearwardly-projecting heel 61, which preferably inclines rearwardly and downwardly, as indicated, having the same downward direction as the upper rear face of the beam and projecting rearwardly beyond the beam, as indicated. To the rear lower face of the beam a clip or plate 62 is attached, the upper edge whereof is bent laterally, as indicated, in order to constitute a seat for a stud 63. This stud extends downwardly through an enlarged opening 64 in the projecting extremity of the heel 61. The body of the stud is preferably threaded and carries an adjusting-nut 65, the face whereof rests against the face of the heel 61. The upper extremity of the stud 63 is provided with a cap or washer 66, preferably held in position by a removable nut, as shown, and against this cap a helical spring 67 thrusts, the lower extremity of the spring being disposed against the upper face of the heel 61. With this arrangement, of course, the spring 67 operates to constrain the beam in an upward direction toward its rear; but evidently by adjusting the nut 65 the exact position of the beam may be changed, with the effect of raising or lowering the forward portion of the cradle, as desired.

In practical operation the fender will normally, of course, occupy the inactive position in which it is illustrated in Figs. 1 and 2, at which time it will be disposed neatly beneath the forward portion of the car-body. If a body should fall upon the track or be discovered immediately in front of the car, in throwing off the current the circuit 52 would be closed through the solenoid 51, whereupon the core 50 would be drawn into the interior of the coil, as will be readily understood. This would of course pull the link 45 forwardly and would operate to withdraw the head 41 from the throat 34, releasing the

tongue 59, as will be readily understood. Immediately upon the release of the tongue 59 the helical springs 13 operate instantly to throw the plungers 10 rearwardly and bring the fender into its active relation, as indicated in Fig. 3. The fender would be reset simply by hand, as there would be few occasions for its actual use.

Attention is called to the fact that by reason of the construction described the cradle of the fender when in its inactive position is disposed in substantially the same relation with respect to the track that it has when in its advanced or active position, and hence the fender would operate, probably, to save the life of a person falling beneath the car, even though the forward portion of the car had passed above his body. Also when the fender is in its inactive or folded position it constitutes a substantial guard for the forward wheels of the car-truck.

Having thus described my invention, I claim as new and desire to secure by Letters Patent—

1. In a fender, in combination, a cradle, pivoted arms supporting said cradle, means for normally maintaining said cradle in an inactive position beneath a car-body, means for constraining said arms to throw said cradle forwardly, and means for releasing said arms.

2. In a fender, in combination, a cradle, arms carrying the same, means for restraining said cradle in an inactive position beneath a car-body, springs constraining said arms to project said cradle forwardly, a link supporting said cradle independently of said arms, and means for releasing said cradle.

3. In a fender, in combination, arms pivotally mounted beneath a car-body, a cradle supported upon the said arms, a cushion attached to said cradle, links supporting said cushion, means for constraining said arms to advance said cradle, and means for releasing said cradle.

4. In a car-fender, in combination, a cradle, arms carrying the same and attaching pivotally beneath the car-body, a cushion attaching to said cradle and projecting forwardly, links supporting said cushion, locking means for securing said cradle beneath the car-body, releasing means, and means for constraining said arms to advance said cradle.

5. In a car-fender, in combination, a cradle adapted to swing forwardly, a tongue carried by said cradle, a catch coöperating with said tongue and maintaining said cradle beneath said car-body, and means for releasing said catch.

6. In a car-fender, in combination, a cradle adapted to swing under the car-body, a tongue projecting upwardly and rearwardly therefrom, brackets attaching to the under side of said car-body and presenting a throat therebetween adapted to receive said tongue, a catch located at said throat and operating to lock said tongue within the throat and means for controlling said catch.

7. In a car-fender, in combination, a cradle adapted to swing under the car-body, a tongue carried by said fender projecting upwardly and rearwardly therefrom, brackets carried under said car-body and presenting a throat therebetween adapted to receive said tongue, a catch mounted at said throat and having an edge lying in the path of said tongue in entering, whereby said catch may be deflected, said tongue presenting an edge engaging said catch, springs constraining said fender into an active position, and means for releasing said catch.

8. In a car-fender, in combination, a cradle, arms pivotally attached under the car-body and supporting said cradle, means for controlling said arms, a cushion attached to said cradle forwardly of said arms, and links attached to the side bars of said cushion and also attached under said car-body.

9. In a car-fender, in combination, a cradle adapted to swing from under the car-body, means for constraining said cradle into its active relation, a catch normally restraining said cradle beneath the car-body, a solenoid in connection with said catch, and means for closing the circuit through said solenoid.

10. In a car-fender, in combination, brackets attached under the car-body, arms pivotally attached to said brackets, a beam pivotally supported on said arms, a cradle carried by said beam and projecting forwardly therefrom, said arms having extensions beyond the pivot-points thereof, plungers attached to said extensions and projecting rearwardly, springs constraining said plungers in a rearward direction, a cushion pivotally attached to said cradle forward of said beam, links attached to said cushion at substantially the middle points of the side bars thereof, means for supporting said links under said car-body, means for normally locking said cradle under said car-body, and means for releasing the same.

11. In a car-fender, in combination, a cradle, a cushion pivotally attached to said cradle near the rear portion thereof and projecting upwardly and forwardly, and means for supporting said cushion and said cradle to swing under the car-body.

12. In a car-fender, in combination, a cradle, means for supporting the same to swing from under the car-body, a pivoted catch coöperating with said cradle to retain the same under said car-body, resilient means in connection with said catch for supporting said cradle, and means for controlling said catch to release said cradle.

13. In a car-fender, in combination, a transverse beam, a cradle carried thereby, a substantially fixed member adjacent to said beam, a stud rigid with said beam, an adjusting-nut carried by said stud and adapted to engage said member, and a spring thrusting against said member and constraining said stud.

14. In a car-fender, in combination, a transverse beam, a cradle carried thereby, means

for freely supporting said beam, a tongue carried by said beam, means for holding said tongue in a substantially fixed position, and means for adjusting said beam with relation to said tongue.

15. In a car-fender, in combination, a transverse beam, a cradle carried thereby, movable arms supporting said beam, a tongue pivotally carried by said beam, means for maintaining said tongue in a substantially fixed position, a stud carried by said beam, a spring

mounted on said stud and thrusting against an extension of said tongue, and an adjusting-nut carried by said stud and engaging said extension.

In testimony whereof I have signed my name to this specification in the presence of two subscribing witnesses.

ELWOOD C. HALL.
